UNITED STATES PATENT OFFICE.

FRANK J. HOKE, OF INDIANAPOLIS, INDIANA, ASSIGNOR TO HOLCOMB AND HOKE MANUFACTURING COMPANY, OF INDIANAPOLIS, INDIANA, A CORPORATION.

DESIGN FOR COMBINED PHONOGRAPH AND MUSICAL-INSTRUMENT CABINET.

Application filed July 25, 1927. Serial No. 22,863. Term of patent 7 years.

To all whom it may concern:

Be it known that I, FRANK J. HOKE, a citizen of the United States, and a resident of the city of Indianapolis, county of Marion, and State of Indiana, have invented a new, original, and ornamental Design for Combined Phonograph and Musical-Instrument Cabinet, of which the following is a specification, reference being had to the accompanying drawings, forming a part thereof.

In the drawings, Figure 1 is a front perspective of the design. Figure 2 is a side perspective thereof.

I claim:

The ornamental design for combined phonograph and musical instrument cabinet, as shown.

FRANK J. HOKE.
